By his attorney
UNITED STATES PATENT OFFICE.

FRED L. TURNER, OF PHILADELPHIA, PENNSYLVANIA, ASSIGNOR TO THE KEYSTONE WATCH CASE COMPANY, OF SAME PLACE.

WATCH-BOW FASTENER.

SPECIFICATION forming part of Letters Patent No. 414,828, dated November 12, 1889.

Application filed July 13, 1889. Serial No. 317,377. (No model.)

To all whom it may concern:

Be it known that I, FRED L. TURNER, of the city and county of Philadelphia, and State of Pennsylvania, have invented an Improvement 5 in Watch-Bows, of which the following is a specification.

My invention has reference to watch-bows; and it consists of certain improvements, which are fully set forth in the following specification and shown in the accompanying drawings, which form a part thereof.

It has been proposed to provide a watch-pendant with a bow hinged to it and positively held thereto by a tubular-locking piece which 15 fits into the pendant, and is formed with slots or notches adapted to encircle the ends of the bow and constructed to fit into the annular grooves formed thereon. This is clearly set out in Letters Patent No. 300,706, dated June 20 17, 1884, to David Glickman.

My invention is an improvement upon the structure set out in that patent; and it consists in forming the tubular locking-piece with screw-threads, whereby it may adjustably be secured to the pendant and adapted to put any degree of friction on the bow, so that it shall not be too loosely connected to the pendant.

In the drawings, Figure 1 is a sectional elevation of a watch pendant and bow embodying my invention. Fig. 2 is an elevation of the locking-piece removed, and Fig. 3 is a plan view of same.

A is the pendant, and is provided with the 35 holes B, arranged diametrically opposite for the ends of the bows C, and is also internally screw-threaded at its top or upper part, as shown at F. The bow C is journaled in the holes or sockets B, and its ends are formed 40 with annular grooves c to form heads upon the ends. These heads may be formed in any other way desired.

D is the annular locking-sleeve, and has a smooth lower part d, adapted to fit into the 45 annular grooves c of the bow, and a screw-threaded upper part, as at E, which is designed to screw into the threads F in the pendant. This locking-sleeve may have notches G whereby it can be screwed in or out 50 by the proper tool.

It is quite evident that the annular grooves c need not extend all the way around the ends of the bow, as said bow cannot make a complete revolution on the pendant.

It will now be understood that after the 55 bow has been snapped in place on the pendant the annular sleeve D may be screwed down so that its edge d fits into the grooves c of the bow, and, owing to the fact that the sleeve D has no notches or slots to fit around 60 the ends of the bow, there is nothing to prevent such adjustment as may be desired to vary the friction due to the pressure of the part d upon the ends of the bow. By making the pitch of the screw-threads small there 65 is no tendency of the sleeve D to work loose; and it is also to be borne in mind that any action of one end of the bow on the sleeve D to rotate it is counteracted by a similar action by the other end of the bow, thus preventing 70 the movement of the bow inducing any tendency to looseness.

Having now described my invention, what I claim as new, and desire to secure by Letters Patent, is—

1. The combination of a watch-case pendant, a bow journaled therein and having its ends extended within the pendant and formed with heads, and an annular locking-sleeve 80 screwed into the pendant and having its end extending back of the heads of the bow ends.

2. The combination of a watch-case pendant, a bow journaled therein and having its ends extended within the pendant and formed 85 with heads, and an annular locking-sleeve screwed into the pendant and having its end made smooth and extending back of the heads of the bow ends.

3. The combination of a pendant, a bow 90 journaled therein and having its ends formed with grooves, and an adjustable locking-sleeve made annular and screwed into the pendant and having its lower edge extending into the grooves of the bow.

4. The combination of a pendant, a bow 95 journaled therein and having an end formed with a head, and a rotatable and adjustable annular sleeve contained within the pendant, having a continuous lower edge fitting 100 back of said head and permitting rotation of both the bow and the sleeve.

In testimony of which invention I have hereunto set my hand.

FRED L. TURNER.
